(57) **CLAIM**

The ornamental design for a packaging container for an audio component, as shown and described.

DESCRIPTION

FIG. 1 is a perspective view of a packaging container for an audio component according to our new design;

FIG. 2 is a side view thereof; and,

FIG. 3 is a top view thereof.

The broken lines in the drawings showing the inside elements of the container for an audio component illustrate portions of the design that form no part of the claim. The broken lines on the top surface of the container closure in FIGS. 1 and 3 represent unclaimed lines on a claimed surface.
